fluid passes to a condenser forming a part of the refrigerating apparatus and hereinafter referred to, the lubricating and sealing liquid discharged from the compressor gravitating to the bottom 5 of the housing 36 and after conditioning, as hereinafter described, being returned to the inlet of the compressor.

The compressor 10, shown as of the well known intermeshing herring-bone gear type communicates at its inlet 37 with a pipe 38 and at its outlets 39, located at opposite ends of the compressor, with pipes 40 which open into a pipe 41, the pipe 41 opening at its upper end into a passage 42 in the plate portion 21 and registering with a passage 43 in the bushing 30 and communicating with the recess 31, this recess also communicating with a passage 44 in the opposite side of the bushing 30 and which communicates with a passage 45 diametrically opposed to the passage 42 15 and opening at its outer end into a pipe 46 having a down-turned end 47 terminating directly above the recess 24, whereby the compressed gaseous refrigerant and the lubricating and sealing liquid discharged from the compressor traverses the 20 passages and pipes just described finally discharging at a point above the recess 24, the liquid discharging from the pipe 46 maintaining a body of lubricating liquid around the shaft 17 and the 25 excess liquid overflowing to the bottom of the housing, the compressed gaseous refrigerant rising in the housing 36.

The condenser above referred to and into which the gaseous refrigerant compressed by the compressor 10 is discharged, is represented at 48 and is shown as of the type comprising an upper header 49 in communication at one end with the top portion of the housing 36, through the medium of a pipe 50, a lower header 51 forming a receptacle and a series of vertical pipes 52 opening at their upper and lower ends, respectively, into the headers 49 and 51. The condenser 48 may employ any desirable cooling means therefor, the condenser being shown as air-cooled, as for example by a motor-driven fan indicated at 53.

It may be here stated that in the operation of the apparatus the refrigerant liquefied in the condenser 48 discharges into the receptacle 51 wherein it accumulates and from which it passes through a valve-controlled port as disclosed in my said pending application Serial No. 512,671 50 into a pipe 55 and through a valve device 56 hereinafter referred to and thence through a pipe 57 into the refrigerating element, or evaporator, 58, which may be of any desirable construction that shown being of a common and well known form and in which the liquefied refrigerant supplied thereto, in evaporating, produces the refrigerating temperature in the chamber in which the refrigerating element 58 would be located in use. The top of the refrigerating element 58 is connected with the pipe 38 for leading the gasified refrigerant from the refrigerating element back to the compressor 10.

The apparatus shown incorporates means for 65 conditioning the sealing liquid in accordance with the invention described in my pending application for United States Letters Patent Ser. No. 381,862, filed July 29, 1929, for improvement in refrigeration. The particular construction of 70 these means illustrated herein is the same as that shown in my pending application Ser. No. 512,671, and comprises a pipe 59 which opens into the bottom of the container 36, a flat coil 60 shown as connected at its upper end with the pipe 59 and flatwise opposing, and in contact

with, the series of pipes 52, and a cylindrical pipe coil (not shown) located in the receptacle 51, one end of which is connected with the lower end of the coil 60 and the opposite end of which is connected with a pipe 62 which communicates with a port 63 in the casing of the compressor and shown as located midway between the ends of the intermeshing gears of the compressor and so positioned as to communicate with the space between the gears at their points of initial intermesh. By the arrangement shown the lubricating and sealing liquid during the operation of the compressor, is continuously drawn from the body thereof in the bottom of the housing 36, thence passed through the coil 60 and the coil in tank 51 wherein it is subjected respectively to the cooling effect produced by the fan 53 and the temperature of the liquefied refrigerant and then introduced into the interior of the compressor for performing the sealing and lubricating functions.

In the operation of the apparatus a body of liquefied refrigerant is maintained in the receptacle 51 as hereinafter described and in which body the coil in the receptacle 51 extends whereby the sealing and lubricating liquid in this coil is caused to be in heat-interchange relationship with the liquefied refrigerant in the receptacle 51, whereby the temperature of the sealing and lubricating liquid, due to its subjection to the temperature of the condensed refrigerant, rises and falls substantially in step with the rise and fall of the temperature of the condensed refrigerant, the temperature of which latter rises and falls responsive to the heat of the compressed gaseous refrigerant discharged from the compressor, regardless of variations in the relative quantities of gas and oil discharged from the compressor, with the resultant high efficiency in the operation of the apparatus as fully set forth in my above referred to pending application for patent.

In accordance with the preferred illustrated embodiment of my invention, provision is made for continuously circulating the gaseous fluid from the housing 36 to the condenser and from the latter back to the housing, for the purpose of cooling the motor and producing flow of the compressed refrigerant from the housing to the condenser, the apparatus to this end being provided with a pipe 64 which connects at one end with the upper end of the liquefied refrigerant receptacle 51 and which opens at its other end into the housing 36 preferably through the shroud member 34 above the fan 12, the fan in operating producing suction in the pipe 64 with resultant circulation of the gaseous refrigerant. The fan 12 is of such capacity that it will circulate gases in a quantity sufficient to insure the proper cooling of the motor by convection currents regardless of the volumetric discharge of the compressor.

It is desired that there be maintained at all times a passage through which a portion of the compressed gaseous refrigerant discharged from the housing 36 is returned to the latter to thus effect the continuous circulation above described.

In the particular construction shown, means are provided for preventing the liquefied refrigerant from rising in the receptacle 51 to the pipe 64, these means comprising the system of valves disclosed in United States Letters Patent No. 1,759,534 granted to me May 20, 1930, the lower valve device which controls the port above referred to and through which the liquid refrigerant

- erant is supplied from the receptacle 51 to the pipe 55 and operates to open this port when the liquid refrigerant rises in the receptacle 51 above a predetermined level, being located in the receptacle 51, and the upper valve device and corresponding with the upper valve structure 23 of the patent referred to and serving to prevent substantial evaporation of the liquefied refrigerant while in the pipe 55, being represented at 56.
- 10 The valve structure 56 serves to maintain throughout the range of the temperatures of the condensing medium a substantially low and uniform differential pressure at opposite sides of the lower valve device above referred to, resulting in 15 the actuating of the discharge by a substantially constant-level of liquid refrigerant in the receptacle 51 which, as shown, is below the pipe 64.
- In the construction shown, means are provided for leading portions of the sealing and lubricating liquid to the bearings for the rotating parts of the compressor, the means shown comprising a passage 69 communicating at one end with the port 63 and at its opposite end with a vertical passage 70 having a lateral branch 71 opening into 25 the journal portion 72 provided in a disk 73 positioned in the compressor-casing and in which disk the stub shaft 74 of one of the gears is journaled. The lower end of the passage 70 connects with a lateral passage 75 which opens through a port 76 30 into the journal portion 77 of another disk 78 in the compressor casing for the other stub shaft 79 of this gear, the passage 75 opening through a port 80 into the journal portion 81 of another disk 82 in the compressor casing in which the 35 stub shaft 83 carried by the gear to which the shaft 17 is connected, is journaled. Thus in the operation of the compressor temperature-conditioned lubricating liquid is supplied to the journal bearings for these several stub shafts, as well 40 as to the journal bearing for the shaft 17 supplied with lubricating liquid by reason of the bath thereof maintained in the recess 24.
- It will be understood from the foregoing that by providing means for effecting the flow of the 45 compressed gaseous refrigerant from the receptacle (exemplified by the housing 36) into which the compressor discharges, into the condenser without the addition of heat and particularly by providing for the return of gaseous refrigerant 50 from the condenser to the receptacle, stratification of the gases in the receptacle and which are non-condensable at the pressures produced by the apparatus, the effects of hydraulic friction and of counter-currents produced in the condenser, 55 with resultant impedance to the flow of the gaseous fluid to the condenser, are minimized. Furthermore, the apparatus functions at a lower differential temperature between the receptacle and the condenser than in the case of structures 60 wherein thermal means are provided for inducing the flow of the compressed refrigerant to the condenser, resulting in consequent low pressure in the receptacle and decreased impregnation of the sealing and/or lubricating fluid with the gaseous refrigerant.
- 65 In the arrangement shown wherein the motor is located in the receptacle into which the compressor discharges the induced flow of gaseous fluid in the housing not only serves to effect the result just described but also serves to cool the motor by the convection currents produced without the supply of additional heat to the receptacle or its contents and, when the condenser is provided with a return connection to the housing as described, regardless of the volumetric displacement of the compressor.
- Another feature of great advantage is that of reducing to the minimum the possibility of heat transference from the motor to the compressor and to the sealing and lubricating liquid, with a view to effecting substantially adiabatic compression which object is substantially accomplished in the arrangement shown and involving the sealing and lubricating liquid conditioning by subjection to the temperature controlling effect of the condensed refrigerant and the isolation of the motor from the compressor and the sealing and lubricating fluid from the compressor, so far as the matter of heat interchange is concerned.
- While I have illustrated and described a particular construction embodying my invention, I do not wish to be understood as intending to limit it thereto as the same may be variously modified and altered without departing from the spirit of my invention.
- What I claim as new, and desire to secure by Letters Patent, is:
1. In refrigerating apparatus, the combination of a rotary compressor, a journalling portion for the shaft of the rotor of said compressor and above which said rotor-shaft extends, said portion containing a recess in its upper side at said rotor-shaft, a motor for actuating said compressor, a hollow journalling portion for the shaft of the rotor of said motor providing a space between the ends of said last-referred-to journalling portion and the side of said motor shaft, means opening into said space for conducting the discharge from the compressor into, and through, said second-referred-to journalling portion, means for causing the discharge from said compressor leaving said last-referred-to journalling portion to pass to said recess for maintaining a body of sealing and/or lubricating liquid therein, and a receptacle in which the liquid overflowing said recess is collected, said recess being out of communication with said receptacle.
  2. In refrigerating apparatus, the combination of a rotary compressor, a member in which the shaft of the rotor of said compressor is journaled and above which said rotor-shaft extends, said member containing a recess in its upper side at said rotor-shaft, a motor for actuating said compressor located above said member, a pipe leading from the outlet of said compressor to a point adjacent said recess for maintaining in said recess a body of the sealing and/or lubricating liquid discharged by the compressor from which recess the liquid overflows for collection, the recess being closed against discharge to the overflowed liquid and a housing into which said pipe discharges and into which said recess opens.

GEORGE ANDRESEN.
